RESERVE REFRIGERANT SUPPLY AND APPARATUS

Joseph R. Zwickl, Philadelphia, Pa., assignor to
 Baldwin-Southwark Corporation, a corporation of Delaware

Application July 17, 1934, Serial No. 735,661

12 Claims. (Cl. 62—115)

This invention relates generally to a refrigerating system and more particularly to improved means for compensating for refrigerant leakage from the system.

5 A great deal of difficulty has been experienced in refrigeration systems of moderate capacity due to leakage of the refrigerant, this being especially true with refrigerating systems used in air conditioning apparatus for railroad cars as in this 10 case a train usually stops for only very short intervals of time before reaching its destination, and hence it is either impossible to recharge the system until the destination has been reached or any attempt to recharge the system while the 15 train momentarily stops at intermediate stations will result in inconvenience or train delay together with an excessive maintenance cost caused by the fact that it would be impossible to predetermine the station at which the recharging might be 20 necessary. Hence a large number of service stations should be maintained if full normal air conditioning is to be maintained throughout the trip. However, it is well-known to be impractical to provide such service facilities, and hence cars 25 often travel a considerable distance and length of time without the comfort of air conditioning. It is one object of my invention to overcome these difficulties in a relatively simple and effective manner by providing a reserve supply of refrigerant carried by the train to supply make-up refrigerant to the refrigerating system automatically when needed. While my invention is 30 particularly adapted for railroad cars, yet it is equally adapted to other refrigerating apparatus whether 35 for general air conditioning purposes or otherwise.

A further object is to provide improved control means that is operative to maintain a substantially constant amount of refrigerant in the system irrespective of normal pressure fluctuations there- 40 in. Another object of my invention is to provide an improved apparatus and system whereby a reserve supply of refrigerant may be supplied to a refrigerating system automatically in accordance with variations from normal pressure condi- 45 tions in the refrigerating system.

A still further object is to provide improved means for maintaining a substantially constant amount of refrigerant in the system irrespective of pressure variations created therein by changes 50 in the temperature of a medium to be cooled by the evaporator. In air conditioning apparatus, either air or water is circulated over the evaporator to cool the car, rooms or other enclosures, and the temperature of such medium will vary 55 during the course of the day and night and par-

ticularly when it is being initially cooled. It is during such periods that pressure conditions in the refrigerating system may vary from a maximum to a minimum even with a normal amount of refrigerant in the system. Hence in controlling the addition of reserve refrigerant to the system in accordance with the pressure thereof, it is necessary to take into consideration the foregoing conditions and in this respect it is a more specific object of my invention to provide improved means for imposing a compensating action on the reserve supply control mechanism automatically in accordance with variations in the temperature of the medium to be cooled by the evaporator, this being equivalent to the rate of 10 evaporation or evaporator temperature.

Other objects and advantages will be more apparent to those skilled in the art from the following description of the accompanying drawing in which:

Fig. 1 is a diagrammatic view of a compressor-condenser-evaporator refrigerating system with my improved reserve supply means associated therewith;

Fig. 2 is an enlarged sectional view of the reserve supply control valve.

In the illustrated embodiment of the invention which is shown herein merely for the purpose of disclosing one specific form among possible others that the invention might take, I have provided a 30 refrigerating system including usual elements such as a compressor 1, high pressure discharge line 2, condenser 3, expansion valve mechanism 4 of any suitable type, evaporator 5 and suction line 6 which may lead either directly to the suction 35 ports of the compressor or to the crankcase 7 in case the compressor is of the type which employs the crankcase as a suction chamber. Connected to the low side of the refrigerating system, specifically to the crankcase 7, is a reserve supply of 40 refrigerant 8 adapted to have any usual form of removable connection, diagrammatically indicated at 9, to a pipe 10 leading to a control means generally indicated at 11.

As shown in Fig. 2, the control means prefer- 45 ably comprises a two part casing 12 and 13 with a diaphragm 14 clamped, welded or otherwise suitably secured between said parts. A chamber 15 has communication through a port 16 with a valve chamber 17 which in turn communicates 50 with reserve supply pipe 10. Port 16 is controlled by a suitable valve 18 whose stem 19 is permanently secured to diaphragm 14 as by suitable reinforcing collars 20. The valve is preferably 55 slidably supported in the bore of chamber 17 as

by a fluted guiding member 21 while a spring 22 is interposed between member 21 and an adjustable plug 23. Plug 23 may be soldered or otherwise hermetically sealed in any adjusted position. 5 Leading from chamber 15 is a pipe 24 connected either to the suction chamber in crankcase 7 or to the suction line 6. In the event of said connection being secured to the suction line 6, it is preferable that a relatively small orifice should 10 be inserted in line 24 to minimize pressure variations in the system reacting back on the diaphragm 14. These pressure fluctuations are usually at a minimum in the crankcase, and hence pipe 24 can be connected directly thereto without 15 interposing the restricted orifice in line 24.

The temperature compensating mechanism comprises an outer bellows 26 whose ends are hermetically sealed to diaphragm 14 and to the outer end of an inner bellows 27. The free end of bellows 27 is hermetically secured to a flange of a spring casing 28, thereby providing a thermostatic pressure chamber 29. This chamber is connected by a small pipe 30 to a thermostatic bulb 31 placed in the path of inlet air or other medium 20 flowing over the evaporator 5. A spring 32 is interposed between diaphragm 14 and the closed end of casing 28 while an adjustable screw 33 is adapted to vary the tension of spring 32.

Operation.—When the refrigerating system 30 contains its normal charge so as to not require the supply of any make-up refrigerant, the suction pressure is then of a predetermined value, thereby causing the pressure within chamber 15 to act on diaphragm 14 to move the same against the force of spring 32 to move valve 18 to close port 16. If the temperature of the air or other medium flowing over evaporator 5 should decrease to such a point that very little evaporation 35 takes place, thereby causing the suction pressure to drop, this decreased temperature of the medium is transmitted from thermostatic bulb 31 through pipe 30 to the thermostatic chamber 29, thereby reducing the pressure of the thermostatic liquid therein and thus compensate for the reduced pressure on the other side of the diaphragm 40 in chamber 15. Conversely if the temperature of the medium flowing over evaporator 5 should increase above some predetermined value, then a greater rate of evaporation will take place with 45 a consequent increase in suction pressure. Said increased temperature of the medium will be transmitted from thermostatic bulb 31 to the chamber 29, thereby increasing the pressure on the left side of diaphragm 14 to maintain a predetermined differential with the increased pressure 50 in chamber 15. If refrigerant should leak from the system with consequent reduction in suction pressure, then this reduced pressure is transmitted to chamber 15 thereby permitting spring 55 32 to move valve 18 to open port 16 whereupon reserve refrigerant is supplied from tank 8 through pipe 10 past fluted guide member 21 and through port 16 to chamber 15 and pipe 24 to the suction side of the refrigerating system. As the suction pressure increases to normal, the pressure in chamber 15 will correspondingly increase until valve 18 closes its port 16. It will of course be understood that the pressure of the reserve supply 65 of refrigerant is always greater than the suction pressure during normal operation of the reserve supply.

As a result of the foregoing construction and mode of operation, it is seen that a reserve supply 70 tank may be connected to the refrigerating sys-

tem of any air conditioning apparatus thereby insuring uniform comfort and operating conditions irrespective of any refrigerant leakage, while at the same time insuring automatic operation of the reserve system irrespective of normal variations in suction pressure or variations due to changes in the temperature of the medium to be cooled by the evaporator. If desired, this reserve system may be applied to a reverse cycle refrigerating system used for heating or cooling merely 10 by placing a second thermostatic bulb 31' in the path of medium flowing over condenser 3. This bulb 31' may be connected to thermostatic pipe 30 by a three-way valve or other suitable control 15 33, thus permitting only the bulb to be operative which is associated with the heat exchange element functioning as an evaporator. While a compressor-condenser-evaporator circuit has been shown, it will of course be understood that my reserve supply system may be applied to any refrigerating system employing high and low sides as the broad principle involved herein is to maintain a constant amount of working refrigerant, that is, refrigerant in the refrigerating system, in accordance with variations from normal. 20

It will of course be understood that various changes in details of construction and arrangement of parts may be made by those skilled in the art without departing from the spirit of the invention as set forth in the appended claims. 30

I claim:

1. In combination, a closed refrigerating system, a reserve supply of refrigerant normally maintained separate from said system, and means for admitting refrigerant from said reserve supply to said system automatically in accordance with a decreased amount of refrigerant therein from normal. 35

2. In combination, a refrigerating system, a reserve supply of refrigerant, and a pressure operated valve mechanism for admitting refrigerant from said reserve supply to said system automatically in accordance with variations from the normal amount of refrigerant in the system. 40

3. In combination, a refrigerating system, a reserve supply of refrigerant, a valve controlled passage through which refrigerant is admitted from said reserve supply to said system, and means responsive to variations from a predetermined pressure differential for opening said valve to permit said addition of refrigerant to the system. 50

4. In combination, a refrigerating system, a reserve supply of refrigerant, means for adding refrigerant to said system from said reserve supply automatically in accordance with a diminution of refrigerant in the system, and thermostatic compensating means for controlling said latter means. 55

5. In combination, a refrigerating system, a reserve supply of refrigerant, a valve mechanism for controlling the addition of refrigerant from said supply to said refrigerating system automatically in accordance with a diminution of refrigerant therein, and adjustable means for varying said admission of reserve refrigerant. 65

6. In combination, a refrigerating system, a reserve supply of refrigerant, a valve mechanism for controlling the addition of refrigerant from said reserve supply to said system, a movable member controlling said valve mechanism and subjected on one side to refrigerant pressure in said system and on the other side to a predetermined force. 70

7. The combination set forth in claim 6 further characterized by the provision of means for adjusting the value of said force.
8. In combination, a refrigerating system, a reserve supply of refrigerant, a valve mechanism for controlling the addition of reserve refrigerant to said system, a movable member connected to said valve, means for subjecting one side of said movable member to fluid pressure in said system, and thermostatic control means for subjecting the other side of said movable member to a predetermined force.
9. In combination, a refrigerating system including an evaporator, a reserve supply of refrigerant, means for adding refrigerant to said system for said reserve supply automatically in accordance with a diminution of refrigerant in the system, means for also controlling said addition of refrigerant to said system automatically in accordance with the temperature of a medium flowing over said evaporator.
10. In combination, a refrigerating system having a compressor-condenser-evaporator circuit, a reserve supply of refrigerant, and means responsive to the suction pressure of said circuit and to the temperature of the medium flowing
- over said evaporator for controlling the addition of refrigerant from said reserve supply to said system.
11. In combination, a refrigerating system having a compressor with a suction chamber, a condenser, an evaporator, a reserve supply of refrigerant, a valve mechanism for controlling the addition of refrigerant from said reserve supply to said suction chamber automatically in accordance with diminution of refrigerant in the system, and means for also controlling said addition automatically in accordance with temperature changes in a medium flowing over said evaporator.
12. In combination, a refrigerating system having a pair of complementary high and low pressure heat exchange elements, a reserve supply of refrigerant, valve mechanism for controlling the addition of refrigerant to said system from said reserve supply, and means for also controlling said addition automatically in accordance with the temperature of a medium flowing over whichever one of said heat exchange elements may be functioning as an evaporator.
